UNITED STATES PATENT OFFICE.

HENRY E. BELLEROSE, OF LINCOLN, NEW HAMPSHIRE.

PULP-GRINDSTONE.

1,142,296.

Specification of Letters Patent. Patented June 8, 1915.

Application filed March 24, 1915. Serial No. 16,586.

To all whom it may concern:

Be it known that I, HENRY E. BELLEROSE, a citizen of the United States of America, and a resident of Lincoln, county of Grafton, State of New Hampshire, have invented 5 certain new and useful Improvements in Pulp-Grindstones, of which the following is a full and clear specification, reference being had to the accompanying drawings, in 10 which—

Figure 1 is a radial section of grindstone constructed in accordance with one embodiment of my invention; Fig. 2 a side elevation of the same.

15 In that class of pulp grindstones in which the stones are clamped in place on the shaft by means of a pair of clamping disks threaded on the shaft, it frequently happens that the threaded parts become so firmly 20 stuck together by rust, etc., that the disks have to be broken up in order to remove them from the shaft and enable the stone to be replaced by a new one.

It is the object of my present invention to 25 so construct the clamping devices that the disks may be readily taken apart and removed sectionally if they become stuck on the threaded shaft, thereby making it an easy matter to remove the stone while at the 30 same time avoiding the loss of the disks or flanges.

In the drawing, *a* designates the stone, *b* the usual shaft provided with the usual right and left-hand threads, and *c* the two 35 clamping disks threaded on the shaft and adapted to clamp the stone between them in the usual manner.

In the form of device shown, the body *d*² of the disk is cast in a single piece with an 40 enlarged central opening adapted to receive a hub *h* radially divided into two parts, and interiorly threaded. This hub is provided with an annular shoulder *i* which faces inwardly toward the stone, and abuts against 45 an annular shoulder formed in the hub-receiving hole. From this shoulder inwardly the exterior of the hub tapers and this tapered exterior of the hub fits against a similarly inclined or conical part of the hub aperture. 50 To prevent the hub turning independently of the disk or flange, a key *j* is used. A flange or disk of this construction is screwed

up against the stone in the usual manner, but instead of bearing directly against the stone, a filler *k* of wood is used between the 55 inner face of the disk and the outer face of the stone. If a disk of this type is stuck too tightly to the shaft to be unscrewed in the usual manner, a sectional removal of the disk is accomplished by first removing the 60 wood filler piece or pieces *k* at both sides of the stone. This filler can be chopped out, but in most cases the disks can be turned back away from the stone far enough to loosen the fillers sufficiently to enable them to 65 be readily removed. When the fillers on the opposite sides of the stone are thus removed, there is sufficient play for the stone between the disks so that when the stone is pushed against one of the disks there is sufficient 70 space between the other disk and the adjacent side of the stone to enable the disk body *d*² to be pushed inwardly off the nut-like hub far enough to permit the two parts thereof to be jarred loose from the shaft and 75 removed separately from the eye or hole in the disk, thus releasing the disk body and enabling the stone to be readily slipped off the end of the shaft.

It will be observed that a feature of importance lies in tapering the hub section and having the same fit into a tapering concentric hole in the outer section, as in this way it will require but a comparatively slight initial movement of the outer section to free 85 it from the hub section, thereby rendering it unnecessary to use any thicker packing strips *k* than are usually employed.

Having thus described my invention, what I claim is:

In combination with a threaded shaft, a 90 grindstone, filler pieces and a pair of disks threaded on said shaft so as to clamp the stone, each of said disks being constructed of two concentric sections, one inserted in 95 the other, the inserted section being threaded internally for engagement with the shaft and tapered inwardly externally to fit a correspondingly tapered opening in the outer section, means being provided for keying the 100 two parts together, for the purpose set forth.

In testimony whereof I hereunto affix my signature.

HENRY E. BELLEROSE.
